UNITED STATES PATENT OFFICE.

FRANK E. HOWELLS AND LESTER L. LEACH, OF STEELTON, PENNSYLVANIA, ASSIGNEES
TO BETHLEHEM STEEL COMPANY, OF BETHLEHEM, PENNSYLVANIA, A CORPOR-
ATION OF PENNSYLVANIA.

DEVICE FOR TILTING RAILS.

Application filed March 21, 1921. Serial No. 454,110.

As is well known in the art of making steel rails for railway tracks and the like, the hot rails leaving the rolls are usually carried to a hot bed by a roller line on which they lie 5 in succession longitudinally on their sides, and at the hot bed they are pushed or moved laterally by a sliding action to the surface of the adjacent hot bed, still lying on their sides. For various reasons, including con- 10 venience of handling, it is later necessary to turn them from their side position to an upright position on the hot bed such as they occupy in use. The present invention re- 15 sides in means for removing in succession each rail, as it comes to position opposite the hot bed, from the roller line to the hot bed, and for automatically turning each rail on its longitudinal axis from its side position to an upright position on the hot bed 20 during and by this movement. The novel features of the invention will more fully appear from the following description and claims, taken with the drawings.

In the drawings:

25 Figure 1 is a plan view of an apparatus embodying our invention partly broken away.

Figure 2 is a side view of the apparatus partly broken away.

30 Figure 3 is an enlarged diagrammatic illustration of the means and operation in tilting and turning the rail; and

Figure 4 is a perspective view of a portion 35 of a modified form of stop used in turning the rail.

As shown in Figures 1 and 2, a roller line 10 made up of spaced parallel cylindrical rollers 11 operates as a conveyor to bring rails from the rolls to the hot bed 12 ar- 40 ranged closely adjacent thereto at one side, and preferably at a slightly lower level, the adjacent ends of the rollers being slightly conical to facilitate the removal of the rails laterally from the roller line to the hot bed.

45 The rail 13 normally lies on the rollers on its side, as illustrated in Figures 1 and 2. The hot bed 12 is made up of parallel steel rails 14 spaced apart and carried by suitable supports as is well known.

50 The mechanism for moving the hot rails in succession from the roller line 10 to the hot bed, and turning them to upright position, embodies, in the particular form of the invention illustrated, a shaft 21 mounted to

turn in bearings in the fixed supports 22 on 55 the outer side of the roller line and parallel thereto, and having secured thereto at intervals grooved wheels or rolls 23 over which the cables 24, which are preferably made of wire, pass and by which they are recipro- 60 cated. Any known and suitable means is used for driving the shaft and grooved rolls in either direction to the extent desired in operating the cable. A drag bar 25 of known form is mounted above the surface of the roller line 10 longitudinally thereof at its outer side next to shaft 21, and is pro- 65 vided on its outer side with brackets 26 se- cured thereto and extending downwardly therefrom slightly below the surface of the 70 roller line and hot bed, and they are there secured to the ends of cables 24 by suitable means such as a socket and pivot pin 27. The drag bar 25 has on its other side op- 75 posite the brackets 26 similar brackets 28 extending slightly below the surface of the roller line and hot bed, and cables 29 are secured to them and extend at right angles to the drag bar along the hot bed slightly below the surface, and constitute in effect 80 continuations of cables 24. The cables and brackets are of course arranged between rollers of the roller line 10 and between rails 14 of the hot bed. Secured to the drag bar 25 at intervals on the side facing the hot 85 bed, there are projecting brackets 30 hav- ing outer rail engaging surfaces curved on a vertical plane from a point 31 below the surface of the hot bed, inwardly towards the drag bar, and upwardly and then forwardly 90 at the top on a gradually increasing curve. These brackets may be in the form of verti- 95 cal plates secured at their rear straight edges to drag bar 25 by angle bars 32. The lower portions of these curved brackets normally engage the lower edge of the top part of the rail 13 lying on the roller line; and when the drag bar and these brackets are moved laterally by the action of the cables across the roller line and along a part of the hot 100 bed, the contact of the brackets with the rail cause it to slide laterally over the sur- face without turning on its longitudinal axis from its side position. In order to turn the rail on its longitudinal axis and to bring it 105 into upright position with its wearing sur- face uppermost, ready for convenient han- dling, stops 33 are placed at intervals in a

line across the hot bed parallel to the roller line and at a short distance from it. These stops may be in the form of short angle bars having a vertical flange 34 extending transversely of the line of movement of the rails and projecting slightly above the surface of the hot bed in the path of the rails, and a horizontal flange 35 bolted to a fixed support 36 as shown in Figure 3. As an alternative, a short angle bar 37, having one flange wider than the other, may be pivotally mounted at the angle on the fixed support 38 by means of a pivot rod 39, with the narrow flange 40 resting on top of the support, 15 and the wider flange 41 projecting vertically slightly above the hot bed surface. The angle bar may turn on its pivot in one direction, carrying the wider flange to horizontal position and the narrower flange to vertical position, but when this is done it no longer acts as a stop, since the narrower flange is not sufficiently wide to project above the hot bed surface. When the wider flange is vertical, the narrower flange is on the side 25 opposite to the roller line, resting on the support so that the projecting portion of the wider flange will act as an unyielding stop for a rail moving from the roller line, but may be turned down by pressure from the opposite direction. It will be understood that there are a number of these pivoted angle bar stops secured to the pivot rod 39 so that the operator may by turning that rod bring them into or out of operative 35 position. This serves a useful purpose when it is desired that a rail pass without turning. It will of course be understood that the drag bar 25 is so formed and mounted as to pass over these stops without striking them. 40 The cooperative action of these fixed stops and the curved brackets 30 in turning the rail from side position to upright position is shown in Figure 3 diagrammatically. As here shown, when the drag bar and brackets 45 have moved the rail 13 far enough to bring its lower flanged edge in contact with the projecting edge 34 of the stop 33, that edge of the rail will cease to move forward; and further forward movement of brackets 30 50 will cause the opposite edge of the rail in contact with its inclined surface to slide or ride up that surface, turning the rail on its longitudinal axis by a rolling motion over the stop 34, one intermediate position of the parts during this action being shown in dotted lines in Figure 3. This figure also shows the position of the parts in dotted lines after the rolling action is completed and the rail is in upright position beyond the 55 stops. It will be seen that this rolling action, bringing the rail to upright position, takes place automatically as it is being moved by one continuous operation to the point on the hot bed desired. As heretofore indicated, the operator has control of the

dragging mechanism, and therefore after the rail has been turned to upright position and moved to the point desired, he reverses the mechanism, causing the drag bar to leave the rail there and move back to the roller line to get another rail to be delivered to the hot bed. 70

While we have illustrated and described one particular embodiment of our invention, it will be understood that in its broader aspects the invention is not limited to the specific means shown, covering the various movements and actions described producing the results stated. 75

Having thus described the invention, what is claimed as new and desired to be secured by Letters Patent is:

1. In an apparatus for handling rails, the combination with a rail conveyor, of a laterally extending support for rails at one side of said conveyor, the surface of which is in the same horizontal plane as that of the conveyor, means for moving a rail laterally from said conveyor to position on said support, stop means carried by the support for interrupting lateral movement of a rail thereon without interrupting the movement of the first mentioned means, and means whereby the rail moving means may tilt a rail into upright position about the stop means. 85

2. In an apparatus for handling rails, the combination with a rail conveyor, of a laterally extending support for rails at one side of said conveyor, means for moving a rail laterally from said conveyor to position on said support, stops or projections extending slightly above the surface of said support on a line parallel to the conveyor, the said moving means including members for engaging the rail to move it so constructed and related to said stops as to cause a rail lying on its side to turn on its longitudinal axis as it passes over said stops to an upright position without interrupting said lateral movement of the rail. 100

3. In an apparatus for handling rails, the combination with a conveyor support upon which a rail is initially moved longitudinally, of a fixed support for rails at one side of said conveyor support, means for moving a rail laterally from the conveyor support to a desired position on the fixed support, stop means connected to the fixed support for interrupting lateral movement of a rail with respect thereto, and curved guides carried by the rail-moving means whereby the rail is tilted into upright position during its lateral movement. 115

4. In an apparatus for handling rails, the combination with a rail conveyor, of a laterally extending support for rails at one side of said conveyor, means for moving a rail laterally from said conveyor to desired position on said support, transversely aligned 125

stops projecting slightly above the surface of said support at a short distance from said conveyor, and transversely aligned brackets on said moving means projecting above the 5 surface for engaging at spaced points longitudinally the outer side of the rail, the contact surfaces of said brackets being so curved from the bottom rearwardly, upward and forwardly, that when the forward motion 10 of the rail lying on its side is interrupted by the fixed stops, its contacting side will ride by sliding action up said curved surfaces of the brackets, giving the rail a rolling movement over the fixed stops and bringing 15 it to upright position on the support beyond the stops during the movement of the first mentioned means.

5. In an apparatus for handling rails, the combination with a rail conveyor, of a laterally extending support for rails at one side of said conveyor, means for moving a rail laterally from said conveyor to position on said support, adjustable stops parallel to said conveyor adapted in one position of 20 adjustment to project upwardly slightly above the surface of the hot bed in the path of the laterally moving rail and to unyieldingly resist such movement, but inoperative below the surface in another adjusted position, and brackets on said moving means having curved contacting surfaces engaging said rail and serving when said rail strikes said stops to turn it with a rolling action over said stops into normal upright position.

35 6. In an apparatus for handling rails, the combination with a rail conveyor, of a laterally extending support for rails at one side of said conveyor, means for moving a rail laterally from said conveyor to a desired 40 point on said support, a stop member pivoted below and extending transversely of said hot

bed and having longitudinally spaced portions adapted to freely turn on the pivot upon the side next to the conveyor to a vertical position but not beyond with their upper 45 ends slightly above the surface of the hot bed, and brackets on said moving means having surfaces curved in a vertical plane engaging the outer side of said rail and causing it on striking said stops to turn with a 50 rolling movement on its longitudinal axis over said stops into normal upright position.

7. In an apparatus for handling hot rails, the combination with a roller line conveyor 55 for the rails leaving the rolls and on which the rails normally travel longitudinally lying on their sides, of a laterally extending hot bed at one side of said conveyor, a drag bar extending along said roller line at its outer 60 side immediately above its surface, cables connected to said drag bar at its bottom and passing across said roller line between rollers and along said hot bed slightly below its surface, controlled means for simultaneously 65 and synchronously moving said cables back and forth longitudinally, spaced brackets on said drag bar having surfaces similarly curved on a vertical plane for engaging the side of a rail on said conveyor and moving 70 it laterally from said conveyor to the point desired on said hot bed, and a plurality of aligned stops projecting slightly above the surface of the hot bed in the path of the rail and acting in cooperation with said brackets 75 to turn said rail from its side position to an upright position as it moves over the stops.

In testimony whereof we hereunto affix our signatures.

FRANK E. HOWELLS.
